UNITED STATES PATENT OFFICE.

CLYDE W. WARREN, OF SAUK RAPIDS, MINNESOTA.

PORCH-SHADE.

1,836,325.

Specification of Letters Patent. Patented Apr. 6, 1920.

Application filed February 3, 1919. Serial No. 274,620.

To all whom it may concern:

Be it known that I, CLYDE W. WARREN, citizen of the United States, residing at Sauk Rapids, in the county of Benton and State of Minnesota, have invented certain new and useful Improvements in Porch-Shades; and I do hereby declare the following to be a full, clear, and exact description of the invention, such as will enable others skilled in the art to which it appertains to make and use the same.

My present invention relates to what is generally designated as porch shades, and has for its object to improve the same in the several particulars hereinafter noted.

The invention is illustrated in the accompanying drawings, wherein like characters indicate like parts throughout the several views.

Referring to the drawings:

Figure 1 is a view partly in vertical section and partly in elevation illustrating my invention as applied to a shade and to support the shade in a position on a porch structure;

Fig. 2 is an enlarged vertical section taken approximately on the line 2—2 of Fig. 1;

Fig. 3 is a fragmentary enlarged section on the line 3—3 of Fig. 1;

Fig. 4 is a view corresponding to Fig. 1, but illustrating a different adjustment of the shade; and

Fig. 5 is a section taken approximately on the line 5—5 of Fig. 4.

The characters *a*, *b* and *c*, indicate respectively the floor columns and roof structure of a porch.

This improved shade is of that type wherein thin wooden slats are woven together or flexibly connected by cords in such manner that they may be readily rolled up. As hitherto constructed, there have been joints at the adjacent edges of the slats through which the light could pass horizontally and through which objects could be seen by a person looking horizontally through such joints.

As an important feature of the present invention, the slats are beveled at the adjacent edges and overlapped in such manner that light can not pass horizontally through the joints and consequently a person can not see objects through the joints of the shade when looking in an approximately horizontal direction. These beveled edges, moreover, form joints which give the de-

sired ventilation, but which will much better shed water than will joints formed in the old way.

My invention also provides an improved means for hanging and adjusting the shade, as will appear in the description of the drawings.

The shade is made up of thin wooden slats connected or woven together by cords 7, and the upper ends of the said cords 7 are interlapped with and secured to a head-strip 8 made up of a multiplicity of rigidly connected slats. To the head-strip 8 near its ends, are attached hanger-brackets 9, the upper ends of which are in the form of hooks 10, the lower ends of which are provided with eyes or guide-loops 11. The hooks 10 are adapted to be hooked into screw-eyes 13 or like devices secured into or otherwise secured to the over-head beam of the roof structure *c*.

Adjusting cords 14 are attached to the brackets 9 below hooks 10 and above the head-strip 8. As shown, this connection is accomplished by passing said cords through holes in said brackets and by knots 14^a in the ends of said cords. These cords are brought down under the lower portion of the shade, thence upward through the guide-loops 11 and the ends of said cords adapted to be adjustably anchored to anchoring brackets 15 and applied to one of the posts *b*. By reference to Fig. 1, it will be noted that one of the cords 14 is passed through the guide-loops 11 of both brackets 9.

As is evident, the shade can be rolled up and its lower portion vertically adjusted by pulling on the two cords 14.

When the shade is supported by the hooks 10 from the eye-bolts 13, its upper portion will not be mounted for vertical adjustment.

When it is desired to mount the shade for vertical adjustments both at its lower and upper portions, the hooks 10 are attached to the ends of secondary adjusting cords 16, and the said cords 16 are passed through the eye-bolts 13 and adjustably engaged to bracket 15 as shown in Fig. 4, by reference to which it will be noted that one of the cords 16 is passed through both of the eye-bolts 13.

Obviously when the shade is supported as shown in Fig. 4, it may by adjustments of the secondary cords 16, be vertically adjusted bodily so as to vary the distance of its upper portion from the roof structure, and by adjustments of the primary cords 14, the lower

portion of the shade may be rolled up and vertically adjusted. Otherwise stated, the shade supported as shown in Figs. 4 and 5, is capable of universal adjustments so that 5 the shade can be rolled up to any desired extent and adjusted bodily to any position. For example, the shade can be half rolled up and then let down against the floor, leaving a large open space above the shade. Such 10 an adjustment is often highly desirable when a porch is used as a sleeping-porch and where the shade is used only to shield the sleepers from the view of passers-by.

What I claim is:

- 15 1. A porch shade made up of slats and cords flexibly connecting the same, said slats having beveled upper and lower adjacent edges that overlap in a vertical direction and cut off the direct passage of light through 20 the joints in a horizontal direction, the said cords being crossed in the joints between the beveled edges of the slats and spacing the said slats in the manner above stated and tending to hold said slats alined in the same 25 plane.
2. The combination with porch shade made up of flexibly connected slats, hanger brackets secured to the upper slat of the shade, said brackets having hook-shaped upper 30 ends and cord-guides on their lower portions, overhead shade supporting guides, primary

shade adjusting cords attached to said brackets, extended under the shade and through the cord-guides of said hanger-brackets, for rolling up and unrolling the shade, and secondary cords passed through said over-head guides and attached to the hooked ends of said hanger-brackets, for bodily adjusting the shade. 35

3. The combination with porch shade made 40 up of flexibly connected slats, hanger brackets secured to the upper slat of the shade, said brackets having hook-shaped upper ends and cord-guides on their lower portions, overhead shade supporting guides, primary 45 shade adjusting cords attached to said brackets, extended under the shade and through the cord-guides of said hanger-brackets, for rolling up and unrolling the shade, and secondary cords passed through said over-head 50 guides and attached to the hooked ends of said hanger-brackets, for bodily adjusting the shade, the hooked ends of said hanger-brackets being engageable at will with said over-head cord guides. 55

In testimony whereof I affix my signature in presence of two witnesses.

CLYDE W. WARREN.
